United States Patent

Des. 237,601
Patented Nov. 11, 1975

237,601

MOTORCYCLE SIDE CAR

Allan W. Lund, 2641 118th Ave. NW.,
Minneapolis, Minn. 55433

Filed June 24, 1974, Ser. No. 481,964

Term of patent 14 years

Int. Cl. D12—11

U.S. Cl. D12—116

FIG. 1

FIG. 2

FIG. 3

FIG. 4

FIG. 1 is a top plan view of a motorcycle side car embodying my new design;

FIG. 2 is a side elevational view thereof, the opposite side being a mirror image of the side shown herein;

FIG. 3 is a front elevational view thereof; and

FIG. 4 is a rear elevational view thereof.

I claim:

The ornamental design for a motorcycle side car, as shown.
